(57) **CLAIM**

The ornamental design for a barbell, as shown and described.

DESCRIPTION

The file of this patent contains at least one drawing executed in color. Copies of this patent with color drawings will be provided by the Office upon request and payment of the necessary fee.

FIG. 1 is a top, front, left perspective view of a first embodiment of a barbell showing our new design;

FIG. 2 is a top, front, right perspective view thereof;

FIG. 3 is a front view thereof;

FIG. 4 is an enlarged partial view of FIG. 3;

FIG. 5 is a rear view thereof;

FIG. 6 is an enlarged partial view of FIG. 5;

FIG. 7 is a left side view thereof;

FIG. 8 is a right side view thereof;

FIG. 9 is a top view thereof;

FIG. 10 is an enlarged partial view of FIG. 9;

FIG. 11 is a bottom view thereof;

FIG. 12 is an enlarged partial view of FIG. 11;

FIG. 13 is a top, front, left perspective view of a second embodiment of a barbell showing our new design;

FIG. 14 is a top, front, right perspective view thereof;

FIG. 15 is a front view thereof;

FIG. 16 is an enlarged partial view of FIG. 15;

FIG. 17 is a rear view thereof;

FIG. 18 is an enlarged partial view of FIG. 17;

FIG. 19 is a left side view thereof;

FIG. 20 is a right side view thereof;

FIG. 21 is a top view thereof;

FIG. 22 is an enlarged partial view of FIG. 21;

FIG. 23 is a bottom view thereof;

FIG. 24 is an enlarged partial view of FIG. 23;

FIG. 25 is a top, front, left perspective view of a third embodiment of a barbell showing our new design;

FIG. 26 is a top, front, right perspective view thereof;

FIG. 27 is a front view thereof;

FIG. 28 is an enlarged partial view of FIG. 27;

FIG. 29 is a rear view thereof;

FIG. 30 is an enlarged partial view of FIG. 29;

FIG. 31 is a left side view thereof;

FIG. 32 is a right side view thereof;

FIG. 33 is a top view thereof;

FIG. 34 is an enlarged partial view of FIG. 33;

FIG. 35 is a bottom view thereof;

FIG. 36 is an enlarged partial view of FIG. 35;

FIG. 37 is a top, front, left perspective view of a fourth embodiment of a barbell showing our new design;

FIG. 38 is a top, front, right perspective view thereof;

FIG. 39 is a front view thereof;

FIG. 40 is an enlarged partial view of FIG. 39;

FIG. 41 is a rear view thereof;
FIG. 42 is an enlarged partial view of FIG. 41;
FIG. 43 is a left side view thereof;
FIG. 44 is a right side view thereof;
FIG. 45 is a top view thereof;
FIG. 46 is an enlarged partial view of FIG. 45;
FIG. 47 is a bottom view thereof;
FIG. 48 is an enlarged partial view of FIG. 47;
FIG. 49 is a top, front, left perspective view of a fifth embodiment of a barbell showing our new design;
FIG. 50 is a top, front, right perspective view thereof;
FIG. 51 is a front view thereof;
FIG. 52 is an enlarged partial view of FIG. 51;
FIG. 53 is a rear view thereof;
FIG. 54 is an enlarged partial view of FIG. 53;
FIG. 55 is a left side view thereof;
FIG. 56 is a right side view thereof;
FIG. 57 is a top view thereof;
FIG. 58 is an enlarged partial view of FIG. 57;
FIG. 59 is a bottom view thereof; and,
FIG. 60 is an enlarged partial view of FIG. 59.

In regard to FIGS. 1-60, the broken lines depicting the remainder of the barbell show features that form no part of the claimed design. The cross-hatching indicates knurling. FIGS. 1-6 and 9-12 are shaded with stippling to indicate a color contrast between the areas shaded with stippling and the areas having cross-hatching. The stippling does not represent any particular color, pattern, material, texture, or finish.
